FIG. 8

UNITED STATES PATENT OFFICE

ELMER H. TAIT, OF PORTLAND, OREGON

DEVICE FOR CLEANING DUSTERS OR ERASERS

Application filed May 28, 1929. Serial No. 366,666.

The primary purpose and object of my invention is to clean dusters or erasers used in school rooms for the cleaning of blackboards. It has for its object the cleaning of the eraser and the removal of the chalk dust particles from the eraser without the liberating of the same in the room where they are being cleaned. The primary object is to clean the object quickly and economically and to collect the dust within a dust collector provided for that purpose.

The invention in its simplest form consists of a housing, a motor driven suction fan disposed within the housing, a removable beater head disposed in bearings rotatably mounted within the housing and means for maintaining the objects to be cleaned in intimate contact with the beater head and a discharge outlet leading from the housing and having a dust collector bag detachably secured thereto. The device in its preferred form is made portable to facilitate moving from room to room.

A further object of my invention consists in providing a machine for use in school rooms and other places that is relatively cheap in first cost and through the use of which the erasers of a large school room or school building may be cleaned without the liberation of dust within the room and the work be accomplished in a fraction of the time that it can now be done with the present equipment.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a top plan view of the device.

Fig. 2 is a side view of the mechanism illustrated in Fig. 1.

Fig. 3 is a longitudinal, sectional view of the device, the same being taken on line 3—3 of Fig. 2 looking in the direction indicated.

Fig. 4 is a fragmentary, sectional view of

the frame of the device illustrating the beater head and the means for maintaining the erasers in intimate contact with the beater head as the same are being passed through. This view is taken on line 4—4 of Fig. 3 looking in the direction indicated.

Fig. 5 is a detailed, sectional, side view of the suction fan and the spindle upon which the same is mounted.

Fig. 6 is a fragmentary, side view of the closure plate removably secured to the frame and after the removal of the same the beater head may then be taken from the machine.

Fig. 7 is a fragmentary, sectional, side view of the mechanism illustrated in Fig. 6 the same being taken on line 7—7 of Fig. 6 looking in the direction indicated.

Fig. 8 is a fragmentary, sectional, side view of the supporting bracket into which one end of the beater head is removably held, the same being taken on line 8—8 of Fig. 4 looking in the direction indicated.

Fig. 9 is a sectional, side view of the housing illustrating the beater head and the supporting table over which the eraser passes, and illustrating an eraser in position within the device and in intimate engagement with the beater head.

Like reference characters refer to like parts throughout the several views.

I preferably form my device of a framed housing 1 having a superposed electric motor 2 removably secured to the housing. A suction fan 3 is disposed upon the armature shaft 5 of the electric motor. The fan is removably secured to the armature shaft 5 and is held thereupon by a locking nut 4 that is in threaded engagement with the lower end of the armature shaft 5. The suction fan has a sleeve 6 disposed upon its lower end having a belt groove 7 in its lower outer surface. A beater head 8 is mounted within the housing. The beater head consists of a shaft 9 having a frictionless bearing 10 disposed in each end.

A plurality of outwardly extending vanes 11 are disposed spirally about the outer surface of the beater head and a groove 12 is formed in and centrally of the beater head about which a driving belt 13 is disposed. One end of the shaft is mounted within a receiv-

ing socket 14 in the side wall of the housing and the opposite end of the shaft 9 is flattened as illustrated at 15 for engagement in an open slot formed in a lug 16 disposed within the housing on a side wall opposite socket 14. The shaft is pressed into position and held in place by the driving belt 13 which is preferably made of live rubber or other material that is under normal driving tension.

10 The under side of the housing is cut away, as illustrated at 17 to permit the beater head to extend substantially below the under surface of the housing. Referring to Fig. 9, a duster or eraser 18 to be cleaned is placed within the

15 cleaner the back of which rests upon a compressible table 19 and the surface of the eraser to be cleaned then contacts with the beater head and the dust liberated from the eraser is withdrawn into the housing of the

20 machine by the suction fan and is discharged therefrom through the discharge outlet 20 and collected within the dust collector bag 21. Compressible elements as springs 22 are disposed upon the spindles 23 and should be of

25 sufficient tension to press the eraser surface of the eraser upward against the under surface 24 of the housing and maintain the same in intimate contact with the beater head. The beater head will normally feed the eraser

30 through the device but feeding may be accomplished by the forcing of the eraser through the machine by the next to be pressed through. The compressible base upon which the back of the eraser rests, due to the compressible elements as the springs 22 and 23,

35 will accommodate erasers of various depths being automatically pressed through the machine.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. A device of the class described, comprising a housing, a power driven fan disposed within the housing, a sleeve disposed centrally of and downwardly extending from the fan, a fan belt groove formed within the lower end of the sleeve, a beater head rotatably disposed within the housing and detachable therefrom, a belt groove formed within and centrally of the beater head, a belt trained about the beater head groove and the sleeve groove, and a depressible table disposed beneath the beater head and adapted to maintain the object being cleaned in intimate contact with the beater head.

2. A device of the class described, comprising a housing, an electric motor removably mounted on the top of the housing hav-

ing its armature shaft disposed within the housing, a fan mounted upon the armature shaft disposed within the housing, said fan adapted to create a suction within the housing for carrying away the dust residue, a sleeve disposed centrally of and downwardly extending from the fan, a beater head disposed within the housing, a belt groove formed on the beater head, a belt trained about said groove and sleeve, and a feeding table disposed immediately below the beater head and adapted to maintain the object being cleaned in intimate contact with the beater head.
